CLAIM

The ornamental design for a contact, as shown and described.

DESCRIPTION

FIG. 1 is a front view of the contact, showing the new design; FIG. 2 is a rear view of the contact; FIG. 3 is a top view of the contact; FIG. 4 is a bottom view of the contact; FIG. 5 is a side view of the contact; and, FIG. 6 is another side view of the contact.

The broken lines showing various elements of the contact are included for the purpose of illustrating non-claimed subject matter and forms no part of the claimed design.
